LIQUID DISPENSER

Joseph B. O'Connor, Lawler, Iowa

Application February 28, 1933. Serial No. 658,987

5 Claims. (Cl. 226—105)

This invention relates to devices for dispensing liquids such as vinegar, cider or the like and the general object of the invention is to provide a dispensing device of this character which embodies a main reservoir or tank and compartments or containers, each having a certain definite capacity, as for instance, one gallon, one-half gallon, one quart, etc., the containers being provided with faucets and the device being so constructed that the several containers will be kept filled from the main reservoir but communication with the main reservoir will be cut off when the jug or other vessel to be filled is put into position beneath the faucet.

A further object is to provide a device of this character which includes a slide or drawer upon which the vessel to be filled is disposed, the slide or drawer being moved inward to carry the vessel beneath the faucet and this action automatically cutting off communication between the main reservoir and the several containers so that no more than the proper measured amount can be drawn from the compartment or container, the opening in the drawer or slide to permit the removal of the filled vessel acting automatically to reopen communication between the main reservoir and the measuring compartments.

A further object is to provide means whereby air may be vented from the compartments to permit them to be emptied as soon as communication between the measuring compartments and the main reservoir has been cut off.

Other objects will appear in the course of the following description.

My invention is illustrated in the accompanying drawings, wherein:

Figure 1 is a vertical section from front to rear through a dispensing structure in accordance with my invention;

Figure 2 is a section on the line 2—2 of Figure 1;

Figure 3 is an enlarged fragmentary section on the line 3—3 of Figure 1;

Figure 4 is a fragmentary vertical section on the same plane as Figure 1 and showing a modified means for closing and opening the valve;

Figure 5 is a fragmentary section on the line 5—5 of Figure 4.

Referring to these drawings, 10 designates an outer casing which may be made of any suitable material such as wood or enameled metal, may be constructed in any suitable manner and be either cylindrical or rectangular in cross section as desired. This outer casing constitutes in effect a main reservoir or storage tank which is desig-

nated 11 and whose bottom is designated 12. Below the main reservoir is a portion 13 which is divided into a plurality of measuring compartments or containers as illustrated in Figure 2.

This portion 14 is divided by means of the interior walls 15 into a compartment 16 adapted to contain one gallon, the compartment 17 adapted to contain a half gallon, a compartment 18 containing one quart and a compartment 19 containing a pint. This is purely illustrative, it is to be understood, and these compartments may be of other capacities than those stated.

The compartments are so arranged that at the junction of the walls 15 all of the compartments, adjoin each other, and at this junction of all of the several compartments 16 to 19, there is formed the opening 20 through the wall 12. This opening 20 will, therefore, discharge into all of the several compartments 16 to 19. This opening 20 may be closed at its lower end by a diaphragm 21 having openings 22 or the opening 20 may be left entirely clear. The bottom 12 of the storage tank 10 immediately surrounding the opening 20 is formed to provide a valve seat 23 and extending upward through the center of the opening 20 is a rod 24 which is concentric to the opening 20 and which is mounted upon the walls 15 at their intersection.

Disposed concentrically to the rod 24 is a tubular valve stem 25 which if vinegar is being dispensed, for instance, will be of wood, though obviously I do not wish to be limited to the use of this material.

This valve stem extends upward entirely through the chamber 11 and at its lower end the valve stem is provided with the sleeve 26 which may be made of rubber or like material, the lower end of this sleeve being extended inward as at 27. This sleeve constitutes the valve proper carried by the stem and seats against the seat 23, the portion 27 projecting inwardly beyond the seat 23 and over the opening 20.

As before remarked, this valve stem 25 is tubular and the interior diameter of the lower portion of the valve stem is somewhat larger than the rod 24. This tubular interior of the valve stem is enlarged and disposed within this enlarged portion is an air vent valve 28 which is adapted to seat upon the annular shoulder 29 forming the lower end of the enlarged portion 27 of the valve stem 25. The air vent valve 28 is provided with a stem 30 which extends upward nearly to the upper end of the tubular valve of stem 25 and at its upper end is engaged by a coiled compression spring 31 which bears against a pin 110

or collar 32 carried by the spring 30, the upper end of this spring bearing against a cap or closure 33 formed with vent openings 34.

A perforated metallic cap 35 may rest upon this closure 33 and be engaged with the valve stem in any suitable manner or such a metallic cap 35 may be omitted.

The upper end of the valve stem 25 extends beyond the upper end of the storage tank and the upper end of the valve stem is operatively connected to a lever 36 whose fulcrum is designated 39. This lever may be enclosed within a housing or not as preferred but preferably it is enclosed within a housing. One end of this lever extends out through the housing and is there connected to a depending link 37.

The front of the dispensing tank and particularly of the portion 13 thereof, is provided with a plurality of taps or faucets 38, there being a tap or faucet for each of the several compartments 16 to 19. It will be seen that when the lever 36 is depressed at its outer end, the valve stem 25 will be raised and that as the valve stem is raised, the air valve 28 will lower against its seat 29.

When the valve stem 25 is raised, the valve 27 is raised from its seat 23 and as a consequence, liquid in the storage tank can flow into any one of the various measuring compartments 16 to 19 which happens to be empty. If all of the compartments are empty, all of the compartments will be filled and, of course, if only one of the compartments is empty, that particular compartment will be filled, the air in these compartments passing upward through the opening 20 and up through the liquid in the tank and collecting in the upper portion of the tank 11, thus permitting the discharge of liquid into one or more of the compartments.

As was heretofore stated, one of the objects of the invention is to provide a dispensing device of this character in which communication between the storage tank and the measuring compartments will be cut off automatically when a vessel is disposed beneath one of the faucets and wherein communication will be established between the storage tank and an empty compartment when filled vessel is removed from beneath the tap. To this end, I have provided a sliding element designated generally 39 sliding in guides in the base 40 of the apparatus. This slide is preferably in the form of a drawer, and a connection is provided between the slide and the link 37 such that as the slide is pushed inward, it will act to shift the link 37 upward, thus forcing the valve 26 down against its seat 23 but when the slide is pulled outward, it will pull downward on the link 37, lifting the valve 26 from its seat.

Various mechanisms may be provided to this end and I do not wish to be limited to the particular embodiment or embodiments illustrated.

In Figure 1, I have illustrated the slide or drawer as being mounted upon links 41 which are pivoted at their upper ends as at 42 and pivotally connected at 43 to the slide or element 39, this element 39 being in turn connected by a lever 44 to the link 37 so that as the slide is pushed inward, the link 37 will be raised and as the slide is pulled outward, the link 37 will be lowered, thus acting upon the valve 26 as previously described.

In dispensing liquids with this apparatus as just described the jug or other container is placed upon the slide 39 when the slide is pulled outward. It is then pushed inward so as to carry the jug beneath the proper faucet or tap. Preferably, the slide under these circumstances, will be

formed with a front wall 45 which will act to position the jug exactly beneath the faucet at the time when the slide has been pushed in sufficiently far to entirely close the valve 26 and open the vent valve 28. Then when the proper faucet is turned, the liquid within the particular compartment to which the faucet is connected will be discharged into the jug to a measured amount and when this amount has been discharged, no more liquid can run into the jug. The drawer or slide is then retracted or pulled open, of course, after the faucet has been closed and this automatically opens communication between the storage tank and the empty compartment.

In Figure 4, I show another means for operating the valve by means of the said slide or drawer in which the sides of the drawer or slide 39a are provided with downwardly and rearwardly extending slots, numbered 46. The link 37, under these circumstances, is provided with the cross bar 47, the extremities of which engage in these slots.

It is obvious now that when the drawer or slide 39a is pulled outward, the link 37 will be pulled downward, opening communication between the storage tank and the emptied compartment and that when the drawer is pushed inward to carry a jug or other vessel into position beneath the faucet, the link 37 will be pushed upward, thus closing the valve 26. These are only two means which may be used for automatically opening the valve 26 and closing the vent valve or closing the valve 26 and opening the air vent valve and I do not wish to be limited, therefore, to these particular forms or embodiments except as defined in the appended claims, neither do I wish to be limited to the specific embodiment of my invention as illustrated except as defined in the appended claims.

I claim:

1. A dispenser of the character described including a storage tank, a plurality of measuring compartments with which the storage tank communicates, a valve normally closing communication between the storage tank and the several measuring compartments, taps connected to the measuring compartments, and means acting automatically when a vessel is brought beneath a particular tap to cut off communication between the storage tank and all of said compartments, and acting automatically when the vessel is withdrawn from beneath a tap to reestablish communication between the storage tank and the several compartments.

2. A dispenser of the character described including a storage tank, a plurality of measuring compartments with which the storage tank communicates, a valve normally closing communication between the storage tank and the several measuring compartments, taps connected to the measuring compartments, and means acting automatically when a vessel is disposed beneath a particular tap to cut off communication between the storage tank and the several compartments and open communication between the outside air and the several compartments, said means acting automatically when the vessel is removed from beneath the tap to reestablish communication between the storage tank and the several compartments and cut off communication between the atmospheric air and the interior of the compartments.

3. A dispensing device of the character described including a storage tank, a plurality of

- measuring compartments each connected to the storage tank by a common opening, each of said compartments having a tap, a valve movable into position to close said opening or out of such position, a sliding element adapted to support a jug and when moved inward carrying the jug beneath a selected tap, and means connected to the sliding element for automatically shifting the valve to a position to close communication between the storage tank and the measuring compartments when the said element has moved inward to carry the vessel beneath a tap, said means opening said valve when the sliding element is retracted to permit the removal of the jug from beneath the faucet. 80
- 10 5. A dispensing apparatus of the character described including a storage tank, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 105 taps and cause the opening of the annular valve and the closing of the air valve when the sliding element is pulled outward to carry the receptacle away from said taps. 95
- 15 4. A dispensing device of the character described comprising a storage, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 100 taps and cause the opening of the annular valve and the closing of the air valve when the sliding element is pulled outward to carry the receptacle away from said taps. 90
- 20 5. A dispensing device of the character described comprising a storage, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 105 taps and cause the opening of the annular valve and the closing of the air valve when the sliding element is pulled outward to carry the receptacle away from said taps. 100
- 25 5. A dispensing device of the character described comprising a storage, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 105 taps and cause the opening of the annular valve and the closing of the air valve when the sliding element is pulled outward to carry the receptacle away from said taps. 105
- 30 5. A dispensing device of the character described comprising a storage, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 105 taps and cause the opening of the annular valve and the closing of the air valve when the sliding element is pulled outward to carry the receptacle away from said taps. 110
- 35 5. A dispensing device of the character described comprising a storage, a plurality of measuring compartments disposed below the storage tank, the bottom of the storage tank having a single opening communicating with all of the measuring compartments and constituting a valve seat, an annular valve coacting with said seat and having a tubular valve stem, the hollow interior of the stem being formed with a valve seat, an air valve disposed within the tubular stem and urged to its seat, the several compartments having taps, a sliding element adapted to support receptacles to be filled through said taps, a lever connected to the upper end of the tubular valve, a link depending from the lever, an operative connection between the sliding element and said link to cause the closing of said valve and the opening of the air valve when the sliding element is pushed inward to carry a receptacle beneath one of the 105 taps and cause the opening of the annular valve and the closing of the air valve when the sliding element is pulled outward to carry the receptacle away from said taps. 115
